(57) **CLAIM**

The ornamental design for a handle for a suturing instrument, as shown and described.

DESCRIPTION

FIG. 1 is a top, front, left perspective view of a handle for a suturing instrument, with the trigger in an un-actuated position, showing our new design;

FIG. 2 is a bottom, front, right perspective view of the handle for a suturing instrument of FIG. 1;

FIG. 3 is a left side view of the handle for a suturing instrument of FIG. 1;

FIG. 4 is a right side view of the handle for a suturing instrument of FIG. 1;

FIG. 5 is a top side view of the handle for a suturing instrument of FIG. 1;

FIG. 6 is a bottom side view of the handle for a suturing instrument of FIG. 1;

FIG. 7 is a front side view of the handle for a suturing instrument of FIG. 1;

FIG. 8 is a rear side view of the handle for a suturing instrument of FIG. 1;

FIG. 9 is a top, front, left perspective view of the handle for a suturing instrument of FIG. 1, showing a shaft of the suturing instrument in dashed outline;

FIG. 10 is a top, front, left perspective exploded view of the handle for a suturing instrument;

FIG. 11 is a top, front, left perspective view of the handle for a suturing instrument of FIG. 1, with the trigger in a first actuated position;

FIG. 12 is a left side view of the handle for a suturing instrument of FIG. 11;

FIG. 13 is a top, front, left perspective view of the handle for a suturing instrument of FIG. 1, with the trigger in a second actuated position; and,

FIG. 14 is a left side view of the handle for a suturing instrument of FIG. 13.

The broken lines shown in the figure drawings are included for illustrating environmental structure and form no part of the claimed design.
